DESIGN FOR AN ELECTRIC CIGARETTE AND CIGAR LIGHTER

John B. McFerran, Jr., Louisville, Ky., assignor to
Louisville Electric Manufacturing Co., Louis-
ville, Ky., a corporation of Kentucky

Application April 27, 1939, Serial No. 84,642

Term of patent 7 years

To all whom it may concern:

Be it known that I, John B. McFerran, Jr., a citizen of the United States, residing at Louisville, in the county of Jefferson and State of Kentucky, have invented a new, original, and ornamental Design for an Electric Cigarette and Cigar Lighter, of which the following is a specification, reference being had to the accompanying drawing, forming a part thereof.

In said drawing:

Figures 1, 2 and 3, respectively, are front, side, and rear elevations of an electric cigarette and cigar lighter showing my new design.

I claim:

The ornamental design for an electric cigarette and cigar lighter, as shown.
